PNEUMATIC CUSHION FOR VEHICLES.

1,331,564.

Specification of Letters Patent. Patented Feb. 24, 1920.

Application filed October 18, 1915, Serial No. 56,392. Renewed April 22, 1918. Serial No. 230,170.

To all whom it may concern:

Be it known that I, LUCIEN R. GRUSS, a citizen of the United States, residing at the city and county of San Francisco and State of California, have invented new and useful Improvements in Pneumatic Cushions for Vehicles, of which the following is a specification.

This invention relates to a pneumatic cushion for vehicles, and pertains particularly to devices of the character shown in my prior patent, 1,142,162, entitled Fluid-pressure cushioning and weighing mechanism dated June 8, 1915.

15 The object of the present invention is to provide first, an improved form of piston construction and connection; second, a novel form of cylinder construction which permits the formation of an oil seal between the 20 telescoping cylinders; and third, to provide means which will prevent accumulation or formation of air pockets in the oil chamber, these improvements being the result of experience and of actual operation of the invention.

25 The invention consists of the parts and the construction and combination of parts, as hereinafter more fully described and claimed, having reference to the accompanying drawings, in which—

Figure 1 is a central vertical section through the device, showing the pistons, and parts of the interior tube or cylinders in side elevation.

30 Fig. 2 is a central vertical section on line 2—2, Fig. 3.

Fig. 3 is a cross section on line 3—3, Fig. 1.

Fig. 4 shows the application of the invention.

Referring to the drawings in detail A indicates a cylinder, the upper end of which is closed by means of a head 2 to form a cushion or compression chamber 3. Concentrically positioned within and spaced from cylinder A is a cylinder or barrel 4. This is secured to the head 2 as at 5 and carries a piston 6 on its lower end. Slidably mounted telescope-wise exterior of the barrel 4 and within cylinder A is a cylinder 7, and slidably mounted within the barrel is a piston 8, which is connected to cylinder 7 by means of a piston rod 9 and a socket joint 10, so that the two may move

in unison. The piston 8 divides the interior 55 chamber, formed within head 2, barrel 4 and cylinder 7, into two chambers, the upper of which serves as a cushion or compression chamber, while the lower serves as an oil chamber. The oil chamber is again divided 60 into two compartments 11 and 12 by means of piston 6, and these compartments communicate one with the other by means of a central opening 13 formed in the piston 6, which opening also permits a free move- 65 ment of the piston rod 9 therethrough. By referring to Fig. 2 it will be seen that compartment 11 is of smaller interior diameter than compartment 12. This is of consider- 70 able importance, as will hereinafter be de- scribed.

For the purpose of maintaining a seal between the inner barrel 4, the intermediate cylinder 7 and the main cylinder A a groove 14 has been cut in the upper end and inner 75 side of the cylinder 7. The exterior face of cylinder 4 has also been cut on a taper so as to form a gradual decrease in the exterior diameter, said decrease producing the smallest diameter at the lower end, as indicated at 15, and the largest diameter at the upper end, as indicated at 16. This taper construction produces a loose fit between the inner barrel and intermediate barrel, thus permitting play between same, and also per- 80 mitting the formation of an oil film between same, said oil being admitted by providing an oil cup 17 of suitable construction which introduces oil into the annular space 18, where it flows down and collects in the 85 pocket 14 formed in the upper end of the cylinder 7. An oil seal is thus formed at this point which not only lubricates the contacting faces but also forms a seal to prevent the admission or escape of air between 90 the contacting faces of the cylinders.

Another feature of the present invention is the piston construction as shown. Each piston 6 and 8 is provided with a cup-leather 19, which is automatically expanded 100 by means of an annular follower-head 20 and a coil spring 21, which are introduced between the heads of the pistons and the interior of the cup-leather proper. These coil springs exert sufficient pressure on the fol- 105 lower-heads to force these down within the cup-leather, thus not only forcing the cup-leather into contact with the cylinder walls

but they also automatically serve to take up wear between the contacting parts. The lower end of piston 8 is provided with a concave bottom, as indicated at 22, and the 5 upper end of the piston rod is hollowed out as at 23 to form a fluid passage between compartment 11 and compression chamber 3, said fluid passage being opened or closed by means of a check valve 24 at the upper 10 end, and being in communication with compartment 11 through means of a plurality of radially spaced passages 25 formed at the lower end. These passages are so disposed as to communicate with the pocket 15 formed by the concave end of the piston and will in this manner liberate any air which might otherwise have a tendency to accumulate at this point. Air passages such as indicated at 26 have also been formed in the 20 cup-leather groove of the lower piston 6 to permit the escape of air which might otherwise accumulate in the groove.

In practice chambers 11 and 12 are charged with a liquid such as oil, which 25 also stands normally in the compression chamber 3, an inch or two above the piston, above which level the device is charged with air at a desired pressure through an ordinary form of bicycle valve 28, which is 30 normally covered by the cap 29.

Upon the downward movement of cylinder A and cylinder 4, such as is caused when the vehicle body is being loaded, or which also occurs by jolts when traveling and encountering the irregularities of roadway 35 surfaces, the air in chamber 3 on being compressed above the inelastic oil will support or cushion the load of the vehicle body. Separation of the cylinders which takes 40 place when the body rebounds causes the cylinder 7 to move down in the direction of arrow a. This produces a tendency to create a vacuum in the compartments 11 and 12, this being due to the difference in diameter 45 of the chambers 11 and 12 as previously described. The production of vacuum when the parts are separated checks any rebound and consequently eliminates the so-called catapult effect which is so common in spring 50 supported vehicles. The oil collected in the compression chamber above piston 8 has a tendency to gradually leak down by the piston and the cup-leather 19. This oil is, however, replaced when compression takes place 55 or when the cylinder 7 moves up with relation to piston 6. This coming together of the piston 6 and cylinder 7 forces the oil through the opening 13 into the compartment 11, which is of smaller diameter and capacity. 60 The oil is consequently forced through the radial openings 25, the central passage 23 in the piston rod and by check valve 24 directly into the compression chamber 3, where it is retained by the check valve which immediately 65 closes when the cylinders separate.

Any air admitted to either compartment 11 or 12 will in this manner be trapped in the concave end of the piston 6, and will, consequently, be forced back into the compression chamber ahead of the oil. A perfect 70 lubrication of the several parts is thus maintained, and an oil seal on top of piston 8 is similarly maintained as each stroke of the cylinder forces a quantity of oil back into chamber 3, where it accumulates on top 75 of the piston. The seal maintained by the oil admitted from the lubricating cup 17 prevents admission of air from the exterior, and similarly prevents escape of air from the interior. The oil admitted also thoroughly 80 lubricates the contacting faces of the several cylinders, consequently increasing the life and efficiency of the device as a whole.

One form of attachment to a vehicle body 85 is shown in Fig. 4. The cylinder A is in this instance secured to the vehicle frame by means of a bracket 30, while the intermediate cylinder 7 is secured to one end of the spring as at 31. Everything in the nature 90 of a spring has its own natural period of oscillation. The combination of the steel spring and the pneumatic cushion forms a compound spring or cushion action, each element of which has a different period of 95 oscillation, and by interference the vibrations mutually check each other. The disagreeable and dangerous shocks generally encountered on rough road surfaces are in this manner entirely overcome, and comfortable 100 and easy riding secured.

Having thus described my invention, what I claim and desire to secure by Letters Patent is:

1. A pneumatic cushion device comprising 105 a pair of cylinders, one being of larger diameter than the other, and the smaller cylinder being mounted telescope wise within the larger cylinder, a valved piston within the smaller cylinder dividing the cylinders 110 into a cushion chamber and an oil chamber, a piston having a central opening formed therein secured on the lower end of the smaller cylinder, and said piston dividing the oil chamber into two compartments, one 115 being larger in diameter than the other, and communicating with each other through the central opening and a solid rod secured to the valved piston and extending through the central opening and spaced apart therefrom 120 and connected to the lower end of the larger cylinder.

2. A pneumatic cushion device comprising 125 a pair of cylinders, one being of larger diameter than the other and the smaller cylinder being mounted telescope wise within the larger cylinder, a valved piston within the smaller cylinder dividing the cylinders into a cushion chamber and an oil chamber, a piston secured on the lower end of 130

- the smaller cylinder and dividing the oil chamber into two compartments of smaller and larger diameters, an oil seal between said compartments, means connecting the 5 valved piston with the larger cylinder, a head member forming a closure for the upper end of the smaller cylinder, a third cylinder carried by said head and inclosing the smaller and larger cylinders and means for 10 admitting oil to the space formed between the third cylinder and the smaller cylinder to form an oil seal between the contacting faces of the several cylinders.
3. A pneumatic cushion device comprising 15 a pair of cylinders, one being of larger diameter than the other and the smaller cylinder being mounted telescope wise within the larger cylinder, a valved piston within the smaller cylinder dividing the cylinders 20 into a cushion chamber and an oil chamber, a piston secured on the lower end of the smaller cylinder and dividing the oil chamber into two compartments of smaller and larger diameters, an oil seal between said 25 compartments, means connecting the valved piston with the larger cylinder, a head member forming a closure for the upper end of the smaller cylinder, a third cylinder carried by said head and inclosing the smaller 30 and larger cylinders, means for admitting oil to the space formed between the third cylinder and the smaller cylinder, and an off-set formed in the upper end of the larger cylinder to receive the oil and to form a seal 35 between the larger and smaller cylinders.
4. A pneumatic cushion device comprising a pair of cylinders, one being of larger diameter than the other and the smaller cylinder being mounted telescope wise within 40 the larger cylinder, a valved piston within the smaller cylinder dividing the cylinders into a cushion chamber and an oil chamber, a piston secured on the lower end of the smaller cylinder and dividing the oil 45 chamber into two compartments of smaller and larger diameters, an oil seal between said compartments, a rod connecting the valved piston with the larger cylinder, said valved piston having a concave lower end, a 50 central bore extending therethrough and entering the upper end of said rod, ports in said rod forming a communication between the concavity and the bore, and check valve for closing the upper end of said bore.
5. A pneumatic cushion device comprising 55 a pair of cylinders, one being of larger diameter than the other and the smaller cylinder being mounted telescope wise within the larger cylinder, said smaller cylinder being 60 also tapered on the exterior surface to produce a smaller diameter at the lower end, a valved piston within the smaller cylinder dividing the cylinders into a cushion chamber and an oil chamber, a piston having a 65 central opening formed therein secured on the lower end of the smaller cylinder, said piston dividing the oil chamber into two compartments, one being larger in diameter than the other, and communicating with each other through the central opening, a 70 rod secured to the valved piston and extending through the central opening and a socket connection between the rod and the lower end of the larger cylinder.
6. A pneumatic cushion device comprising 75 a pair of cylinders, one being of larger diameter than the other, and the smaller cylinder being mounted telescope wise within the larger cylinder, a valved piston within the smaller cylinder dividing the cylinders 80 into a cushion chamber and an oil chamber, said piston having a concave bottom, a piston having a central opening formed therein secured on the lower end of the smaller cylinder, said piston dividing the oil chamber into two compartments, one being larger 85 in diameter than the other, and communicating with each other through the central opening, a rod secured to the valved piston, said rod having a passage formed therein 90 communicating at one end with the valve and at the other end with the concave bottom, and a socket connection between the rod and the lower end of the larger piston.
7. A pneumatic cushion device, comprising 95 in combination a pair of telescoping cylinders, a piston carried by one of said cylinders and slideable within the other, forming between said cylinders an upper chamber for air and a lower chamber for 100 oil, a plunger on the end of the upper cylinder operating within said lower chamber and dividing the same into two inter-communicating compartments of differential diameters, packed sliding joints for the piston and plunger, a valved communication between the two chambers, a jacket surrounding said cylinders and forming an oil pocket overlying the joint therebetween, and an external source of oil supply for said 105 pocket, said differential diameter compartments operating upon compression of the cylinders to force oil from the lower chamber into the upper chamber to maintain a seal for said packed joint, and on the extension of said cylinders creating a suction between the walls thereof which tends to draw oil into the lower chamber from said pocket.
8. A pneumatic cushion device, comprising 110 in combination a pair of telescoping cylinders having their walls spaced slightly apart, a piston carried by one of said cylinders and slideable within the other forming between said cylinders an upper chamber for air and a lower chamber for oil, a plunger on the end of the upper cylinder operating within said lower chamber and dividing the same into two inter-communicating compartments of differential diameters, packed sliding joints for the piston and 115
- 120
- 125
- 130

plunger, said packed joints including an upturned, outwardly expanded cup-leather on the piston and a downturned, outwardly expanded cup-leather on the plunger, a 5 valved communication between the two chambers, a jacket surrounding said cylinders and forming an oil pocket overlying the joint between, and an external source of oil supply for said pocket, said differential 10 diameter compartments operating upon compression of the cylinders to force oil from the lower chamber into the upper chamber to maintain a seal for said packed joint, and on the extension of said cylinders 15 creating a suction between the walls thereof which tends to draw oil into the lower chamber from said pocket.

9. An air spring comprising a pair of cylinders mounted one within the other and 20 spaced from each other to form an intermediate annular chamber, a head member to which said cylinders are secured, a third cylinder telescoping into the annular chamber, a piston on the innermost of the first 25 named cylinders slidably mounted within the third cylinder, a piston rod secured to the third cylinder by a socket connection, and a piston secured on the opposite end of said rod slidably mounted within the inner- 30 most of the first named cylinders.

10. An air spring comprising a pair of cylinders mounted one within the other and spaced from each other to form an intermediate annular chamber, a head member to 35 which said cylinders are secured, a third cylinder telescoping into the annular chamber, a piston on the innermost of the first named cylinders slidably mounted within the third cylinder, a piston rod secured to the third cylinder by a socket connection, a piston secured on the opposite end of said 40 rod slidably mounted within the innermost of the first named cylinders; a cup leather mounted on each piston, a tapered spreading 45 head slidably mounted on each piston adapted to enter the cup leather, and a spring be-

hind each spreading head adapted to force said head into the cup leather.

11. An air spring comprising a head member, an inner and an outer cylinder 50 spaced from each other, secured to the head member, and forming an annular chamber between said cylinders, a lower cylinder adapted to telescope into said annular chamber, a head member on the lower cylinder, 55 a piston slidably mounted in the inner cylinder, a piston rod on said piston, a socket joint connecting the piston rod with the head on the lower cylinder, and a piston, secured on the lower end of the inner cylinder 60 slidably mounted in the lower cylinder.

12. An air spring comprising a head member, an inner and an outer cylinder spaced from each other, secured to the head member, and forming an annular chamber 65 between said cylinders, a lower cylinder adapted to telescope into said annular chamber, a head member on the lower cylinder, a piston slidably mounted in the inner cylinder, a piston rod on said piston, a socket 70 joint connecting the piston rod with the head on the lower cylinder, and a piston, secured on the lower end of the inner cylinder slidably mounted in the lower cylinder, said last-named piston having a central passage 75 through which the first named piston rod passes, said passage forming a communication between two chambers formed below and above said piston, a third chamber formed between the head and the first 80 named piston, means for automatically maintaining an oil seal above said first-named piston, and means for supplying oil to the annular chamber.

In testimony whereof I have hereunto set 85 my hand in the presence of two subscribing witnesses.
